UNITED STATES PATENT OFFICE.

SHERMAN HARTER, OF MANSFIELD, OHIO, ASSIGNOR TO THE NEW METHOD STOVE COMPANY, OF MANSFIELD, OHIO.

OVEN-DOOR STRUCTURE.

Application filed September 9, 1926. Serial No. 134,453.

In the manufacture of oven doors of the type now most universally used, it is customary to secure a lining plate against the rear side of the door body, said lining plate 5 acting as a rest for utensils when the door is opened, so as to facilitate insertion and removal of such utensils into and from the oven. The body portion of the door is often coated with porcelain or enamel and in some 10 instances, said body is formed of a peripheral frame and a central panel connected therewith. If this panel is injured, for instance by having its porcelain or enamel coating chipped, and a new panel is to be 15 substituted, difficulty is encountered in removing the lining plate, which operation however is necessary to gain access to the bolts or other fasteners by which the panel 20 is secured to the frame. Moreover, if the fastening means for the door handle work loose, the lining plate must be removed in order to tighten them, and under the present 25 constructions, difficulty is here encountered also. It is the object of my invention however to provide a new and improved oven 30 door construction in which novel provision is made for so securing the lining plate as to permit quick and easy removal thereof whenever necessary, and provision has been 35 made whereby portions of this lining plate securing means act also to effectively brace the corners of the door body, this being particularly advisable if the body be formed from a pressed metal frame and a panel secured thereto.

With the foregoing in view, the invention resides in the novel subject matter herein-after described and claimed, the description being supplemented by the accompanying 40 drawing.

Fig. 1 is a rear elevation of an oven door constructed in accordance with my invention.

Fig. 2 is an enlarged rear elevation of one 45 of the lower corners of the door, parts being broken away and in section.

Fig. 3 is a detail sectional view on line 3-3 of Fig. 2.

Fig. 4 is a second detail section on line 50 4-4 of Fig. 1.

The door body in the present disclosure, comprises a peripheral frame F and a panel P secured thereto in a manner forming no

part of the present invention. In the present showing, the outer edge portion of the 55 frame F is rearwardly curved and is provided with a peripheral, rearwardly projecting flange f, and with an internal, rearwardly facing shoulder S at the juncture of the flange with the major portion of the 60 frame.

A lining plate L is provided for the rear side of the door and when access must be had to the bolts B of the oven handle H or to the securing means for the panel P, this 65 lining plate must be removed. In the present disclosure, the bolts B and additional bolts B', serve as the securing means for fastening the panel P to the frame F, and the nuts of these bolts are between the lining 70 plate L and the door body.

For securing the plate L rigidly in position in such a manner as to permit its detachment whenever necessary, and for the purpose of effectively bracing the corner 75 portions of the door body, I have made the novel provision described below.

Four short metal bars 5 are disposed at the rear side of the door body, within the confines of the flange f, these bars extending 80 obliquely across the corners of said body and having their ends suitably secured to the latter. These bars are formed with threaded openings 6 which are alined with other openings 7 in the lining plate L and screws 85 8 are passed through said openings 7 and threaded into the openings 6 to removably secure the lining plate in place. By this construction, the bars 5 effectively brace the corner portions of the door body and as said 90 bars extend obliquely across the corners of the lining plate L, sufficient bearing surface is provided for the latter, to effectively hold its edge portions against springing either inwardly or outwardly. These edge portions are preferably reinforced by a rearwardly projecting flange f' which fits against the inner side of the flange f and may well 95 rest against the shoulder S, said flange being notched at N to receive the bars 5.

In the preferred form of construction, herein disclosed, each bar 5 is a channel bar with its channel disposed rearwardly. The front portions 9 of these bars, which connect the side flanges 10 thereof, have their ends 105 beveled at 11, and these beveled ends as well

as the ends of said flanges 10, abut the inner side of the flange *f*. The front portions 9 rest against the shoulder *S* and are welded thereto as indicated at 12, spot welding being preferably employed.

The rear or free edges of the flanges 10 are forwardly spaced to some extent from the rear edge of the flange *f*, so that when the lining plate *L* contacts with said edges 10 of the flanges 10, it will be flush with the edge of the flange *f*. The openings 7 in the lining plate, are preferably countersunk by forwardly pressing portions of the plate to form flanges around said openings, as seen in Fig. 4, and the channels of the bars 5 serve to receive these forwardly pressed flange portions, as fully disclosed in said figure.

By providing the novel construction shown and described, or a substantial equivalent thereof, not only is a door construction provided which is exceptionally advantageous when entirely assembled, but the lining plate *L* may be removed whenever necessary, and it will be seen that this plate may again be attached with equal ease.

Excellent results have been obtained from the details disclosed and they are therefore preferably followed. However, within the scope of the invention as claimed, variations may, of course, be made.

I claim:

1. An oven door comprising a rectangular door body having a rearwardly projecting peripheral flange, short bars at the rear side of said body extending diagonally across the four corners thereof within the confines of said flange and having their ends rigidly secured to the door, said bars being formed with threaded openings, a lining plate contacting with the rear sides of said bars and engaging said flange, said plate having openings alined with said threaded openings, and screws passing through the plate openings

and removably engaged with said threaded openings.

2. An oven door comprising a rectangular door body having a rearwardly projecting peripheral flange and an internal shoulder at the juncture of said flange with the major portion of said body, a plurality of short bars at the rear side of said body within the confines of said flange and extending obliquely across the four corners of said body, said bars being rigidly secured against said shoulder and having threaded openings, a lining plate contacting with the rear sides of said flange, said plate having openings alined with said threaded openings, and screws passing through the plate openings and removably engaged with said threaded openings.

3. An oven door comprising a rectangular door body having a rearwardly projecting peripheral flange and an internal shoulder at the juncture of said flange with the major portion of said body, a plurality of short channel bars at the rear side of said body within the confines of said flange and extending diagonally across the four corners of the door, said bars having their channels disposed rearwardly and being each provided with two beveled ends abutting said flange, the front portions of said bars being welded to said shoulder and being formed with threaded openings, a lining plate contacting with the rear edges of said bars, said plate having openings alined with said threaded openings, and screws passing through the plate openings and removably engaged with said threaded openings.

4. A structure as specified in claim 1; said lining plate being provided with a flange around each of its openings, said flange extending forwardly into the bar channels to receive and countersink the screw heads.

In testimony whereof I have hereunto affixed my signature.

SHERMAN HARTER.
